CLAIM

USPC ..... D14/485—495; 345/1.1, 1.2, 2.1—2.3, 3.1,

I claim the ornamental design for a display screen or portion thereof with a graphical user interface, as shown and described.

345/902; 715/763, 810, 836, 837, 846,

715/847, 977

DESCRIPTION

CPC G06F 3/048; G06F 3/0481; G06F 3/04812;

The FIGURE is a front view of a display screen or portion thereof with a graphical user interface showing the new design.

G06F 3/04817; G06F 3/0482; G06F

3/0483; G06F 3/0484; G06F 3/04847;

G06F 3/0485; G06F 3/04855; G06F

3/04886; G06Q 30/00; H03J 1/00; H03J

1/0008; H03J 1/0016; H03J 1/0025;

H04N 5/00; H04N 5/08; H04N 5/14;

H04N 5/222; H04N 5/225; H04N 5/232;

H04N 5/445; H04N 5/44543; H04N 5/45;

H04N 2005/44517; H04N 2005/44521;

H04N 2005/44526; H04N 2005/4453;

H04N 2005/44534; H04N 2005/44539;

H04N 2005/44547; H04N 2005/44556;

The outermost broken line rectangle illustrates a display screen or portion thereof and forms no part of the claimed

(Continued)

design. The remaining broken lines illustrate portions of the graphical user interface that form no part of the claimed design.
